UNITED STATES PATENT OFFICE.

WILLIAM C. EDWARDS, JR., OF KANSAS CITY, MISSOURI.

MEANS AND APPARATUS FOR CONCRETE CONSTRUCTION.

1,013,591.

Specification of Letters Patent.

Patented Jan. 2, 1912.

Application filed June 7, 1910. Serial No. 565,649.

To all whom it may concern:

Be it known that I, WILLIAM C. EDWARDS, Jr., a citizen of the United States of America, residing at Kansas City, in the county of Jackson and State of Missouri, have invented certain new and useful Means and Apparatus for Concrete Construction; and I do hereby declare that the following is a full, clear, and exact description of the invention, reference being had to the accompanying drawings, forming a part of this specification.

The invention relates to concrete structures of all descriptions, such as buildings, reservoirs, sewers, piling, poles, etc., and such as employ wet concrete, or in which the material is plastic, the concrete mixture being sufficiently wet to furnish the necessary amount of moisture to properly crystallize the cement mixed with the aggregate.

The objects of the invention are: First: To afford in work of concrete construction a standard method of reinforcing, such that when the load to be imposed upon the wall, column or other supporting surface has been determined, a standard form and reinforcement may be economically supplied. Second: To provide adequate means to carry the tension stresses set up in concrete structures. Third: To afford a greater protection to the finished wall from the weather; and fourth: The monolithic construction of concrete structures, wherein the temporary form and a reinforcement are combined.

The invention consists in certain novel features of concrete construction, and in the apparatus and the organization of its parts, for accomplishing the invention, hereinafter fully described and claimed.

Figure 1, is a view in perspective of the outer walls, taken from the corner, of a building showing the same in process of construction. Fig. 2, is an isometric view of sections of the reinforcement, and Fig. 3, is a similar view of the interlocked, adjacent sections. Fig. 4, is a vertical, sectional view, taken through the walls of the building, as seen in Fig. 1, showing the keying of the concrete through the reinforcement and the link. Fig. 5, is an isometric view of a flanged seat or bed for the reinforcement, and Fig. 6, is the transverse, flanged reinforcement or bridging in the walls of the concrete. Fig. 7, is a plan view of the interlocking sections of the reinforcement, as seen in Fig. 1. Fig. 8, is a plan view of

one of the links supporting the opposite sections. Figs. 9 and 10 are alternate views of the interlocking portions of the reinforcements, and Figs. 11 and 12 are modifications of the interlocking reinforcement to that seen in Fig. 7. Fig. 13, is an isometric view of the reinforcement section, as seen in Fig. 1, when employed for arches, and Fig. 14, is a view of circular structure with its reinforcement upon the lines of the curved portion of Fig. 1.

Like numerals of reference indicate like parts in all the figures of the drawing.

In the application of the invention to the construction of the walls of a building, upon a solid foundation 20, there is placed in the direction of the length of the walls, and horizontally an equal distance of the length of said walls a bed plate 21, of a proportionate width to the determined width of the completed wall, longitudinal portions 22, of which are bent upwardly a short distance, forming a trough. This plate 21, and its upwardly-extended portions 22 are made with openings 24, corresponding to a series, and preferably staggered, so that the strength of the reinforcement is not diminished.

For the reinforcement of the homogeneous concrete walls 25, longitudinal sections of a thin, self supporting material, such as a continuous plate of sheet metal is employed, one of these sections being shown in Fig. 2. The single section of the plate extends a short distance in height, and at an intermediate point in the length of the plate a short, transverse portion 26, is formed, from which are bent and extended at right angles the short portions or offsets 27 and 28 extending longitudinally in respect to the wall 25. From these angular portions 27 and 28 extend, in opposite directions and transversely to the wall, the portions 29 and 30, which together with the oppositely-alined offsets 27 and 28 form a stud which as shown is in the form of a double U, and extend outwardly the desired distance and in proportion to the load to be carried by the wall, and at which point the plate is bent at right angles, and one length or side 31 extended in a parallel plane with the angular portion 27, and in the longitudinal direction of the wall in one direction, and another portion or length of the plate 32 extended in the other direction and in a parallel plane with the portion 28. These

parts, 26, 27, 28, 29 and 30, of the reinforcement, forms a spacing element or member between the reinforcements 31 and 32. The plates 31 and 32 extend in opposite directions like spacing distances and in proportion to the load to be carried by the walls, so as to obtain the maximum stress in tension necessary to the construction of the wall.

10 The end portions of the plates 31 and 32, of the section, are bent at right angles and extended inwardly, forming the grasping portions 33 and 34, just beyond a line parallel with the respective outer surfaces of the portions 27 and 28, and at which point the portions of the plate are bent at right angles and extended a short distance in the longitudinal direction of the wall, as at 35 and 36, thence bent at right angles and the 15 terminal portions 37 and 38 extended a short distance transversely to the wall 25, and parallel with the respective portions 33 and 34, of the section. These portions 37 and 38, being slightly shorter in length than the intermediate, transverse portion 26, of the section, for the purpose further explained.

In the portions 31 and 32, of the section of reinforcement, are openings 40, which are relatively close to each other, and preferably 20 staggered, these openings being stamped or punched from the inner surfaces outwardly, as seen in Fig. 4, producing a cement-holding lip, these lips being in series, serve to give a grasping surface for the cement concrete. These lips not only serve to strengthen 25 and stiffen the plates 31 and 32 of the reinforcement but also afford a means for spouting the flushing material a considerable distance beyond the line of the outer 30 surfaces of said members 31 and 32 where it is spread. Without the lips only a thin film of the flushed material could be retained on the outer surfaces of the members 31 and 32 which is not sufficient for protection to the 35 reinforcement from the elements. Neither would such a thin film of concrete material on the outer surfaces of the members 31 and 32 be sufficient to allow them to act in their full capacity of tension members. Without 40 a relatively thick coating it is also impractical to leave a finished straight and true wall surface without employing other plastering material. Such a thick coating is provided by means of the material carried out 45 through these lips. The other portions of the section of the reinforcement are cut smooth and clean, to form openings, preferably registering with one another, and of the requisite size for the flushing of a wet concrete. These openings being of any suitable 50 conformation, their size, however, such as to afford the passage of the cement concrete.

Upon the bed plate 21, the section of reinforcement described is placed, extending 55 in the direction of the length of the bed, and

a section of like construction is brought up and placed with its lower single and double U-shaped portions in position above the double and single U portions of the first section, and these grasping parts upon a movement downwardly of the second section 70 interlock, and upon the completion of the downward movement the outer surfaces of the portions 31 and 32 are in perfect alignment vertically and horizontally, the 75 spaces formed between the inner surfaces of the respective portions 31 and 32, of the reinforcement, being spaced apart the width desired for the body of cement concrete. A series of reinforcement sections is now 80 placed upon the bed, in like manner to the above, until the length of the reinforcement is equivalent to the full length of the wall.

It is obvious that to complete the full length of a wall with reinforcement, that the 85 sections especially at the angle formed by two walls as a starting point, will require to be shortened, and in fact a dead end provided for openings, such as for doors and windows. For instance, in starting the wall 90 reinforcement at the corner angle of a building, as seen in Fig. 1, a portion 41, of the outer portion 31, of a section of the reinforcement, is bent inwardly at right angles and extended the width of the section, and a 95 portion 42, bent in U-shape, to reinforce and interlock with one of the U-shaped portions 34, 36, 38, of the outer section of the reinforcement. An abutting reinforcement, as seen in Fig. 1, may consist of two sections, 100 cut away in vertical lines intermediate the lines of the transverse interlocking portions of the reinforcement. This end is then blocked or closed by the employment of one of the bed plates 21, as seen in Fig. 5, set in 105 a vertical position, and the flanged portion receiving the cut portions of the sections, and which in return is placed against the inner surface or surfaces of inner portions 32, of the reinforcement, and is secured to the portion 31 by the link 44, as seen in Fig. 1.

It will be obvious that the interlocking 110 portions of the reinforcement affords a strong reinforcement, when combined with the cement in the wall, and as further shown of varied forms and as a part of the building construction. These perforated 115 interlocking portions divide the reinforcement into separate compartments. The wet concreting material being adapted to be supplied to each compartment to fill the same; the cement concrete in one compartment 120 uniting with the cement concrete in the adjoining compartments through the perforated interlocking portions. The first row or curve of the sections of reinforcement 125 having been laid upon the bed plate 21, the links 44, as seen in Fig. 8, are secured to the portions 31 and 32, and wet concrete is 130

supplied to the reinforcement in such plasticity that the flushing takes place at once, through the openings 40, in the portions 31 and 32, of the sections as shown in Fig. 4, 5 and also through the perforations or openings in the interlocking portions of the sections, the wet cement flushing through and surrounding the interlocking parts bind the sections together. The sections now act as 10 a temporary form to hold the wet concrete vertically in place until the cement concrete has set, sufficient wet material being supplied to the sections to fill the same, and to flush through the openings 40, in the portions 31 and 32, in sufficient quantity and plasticity, so that it may be spread and attain the following object. It is necessary for the proper protection of the tension members 31 and 32 especially in cases where 15 20 the finished structure is exposed to the ravages of fire or weather, that these members shall be protected by a heavy coating of the concreting material, since from any deterioration in its outer surfaces the structure might fail by the destruction of the bond between the concreting material and the reinforcement. It is an established rule in concrete construction that the tension reinforcing members must be embedded in the 25 30 concreting material a distance of not less than one half inch and from that up to two inches from the surface. These sections are now full of wet concrete material, and may be slightly out of plumb vertically. If so, 35 they are brought to a vertical position by manipulation of the hand, then the material which has flushed through the openings of the sections 31 and 32 is spread on on both surfaces by means of a wooden or cork float, 40 and a fine, smooth, sand finished plastered outer layer 45^x is obtained, which becomes keyed to the lips of the opening 40, and homogeneous with the cement aggregate on the inner surfaces of the sections of reinforcement when "set." The outer layer or 45 50 plastering may be of any required thickness, and if a white coat is desired, a single application is all that will be required. This method saves plastering material and the cost of applying the same.

In the erection of partition walls the space between the portions 31 and 32 may be narrowed to the limit of safety in concrete construction, and with the plastering a saving 55 in the thickness of wall attained, which is frequently of much importance in rooms of small dimensions. The links 44, which are hooked at each end and pass through the openings in the portions 31 and 32, of the 60 sections, engage with adjacent openings and serve to hold the said portions of the sections from any distortion of the reinforcements in the placing of the cement concrete. Upon the completion of the finishing of the 65 wall construction to the height of the lower

sections of reinforcement, a plate 45, of the same width of the plate 21, is employed as seen at Fig. 6, with broken portions 46, of the flanges, which are alternately extended upwardly and downwardly, the downwardly-extended portions extending upon the outer surfaces of the portions 31 and 32, of the sections of the reinforcement and assist in retaining these portions in alignment and from spreading, and also serve as 70 a bridging, giving great stiffness horizontally through the wall. These plates are provided with openings 24^x the same manner as the bed plate 21, and form a bed upon which another row of interlocked sections 80 of reinforcement is mounted, the alignment of these sections being retained vertically thereby. Upon the completion of a second tier of sections, the cement concrete is supplied thereto, and the outer layer finished, 85 as before described, and this process repeated until the height desired for the wall is reached. Upon the hardening of the concrete, the sections cease to act in the capacity of a form, and the portions immediately adjacent to the interlocking parts of the sections obtain a solidity of column construction and members 31 and 32 afford great tensile strength and all stress set up 90 in the wall is thus amply provided for. 95

In Fig. 1 the width of the section, as at 47, is widened to afford the space necessary for a chimney construction, the core 48 remaining to hold the concrete. In this construction the bed plate, 21 may be employed 100 at the openings for doors or windows, and to cut terminals of the portions 31 and 32, of the sections, blocks 49 are secured by staples 49^x. Thus, a securing surface is 105 formed for the door and window frames, and to which interior finish may be attached. The use of the trough 21, in various lengths, is utilized for openings, and especially takes the place of a lintel above the door or window opening, when the cement has hardened. For the purpose of joining the dead ends of walls to other structural parts, and for leaving spaces in the concrete 110 for weight boxes on window frames, and like purposes, the body of the trough 21 is 115 varied, as seen at the end of the wall on Fig. 1, and the parts simply bent to form two right angles 21°, from a central portion 21°, extending in the direction of the wall. 120

In order to provide for the tension stresses which may vary in wall and column construction, I have discovered the necessity in the construction of the reinforced building or structure, as embodied in my invention, for providing for such changes from the immediate construction, as shown in Fig. 1, to the interlocking parts as shown in Fig. 9. In this construction, the parts corresponding to 26, 27 and 28, of Fig. 1, instead of being formed on the basis of angles 125 130

are given the curved form as seen in Fig. 12. In this modification the single connecting tie 82 is integral with both longitudinal reinforcements 79 and 80, of a single section, 5 the interlocking portions 81 and 77, of the tie being separated from each other, the curved lines, however, of the tie being of an S-shape, so that the grasping ends 78^x and 79^x form a clench, around the bends 82, preventing accidental disengagement of the tie. 10

In Fig. 10 both interlocking parts 83 and 84, of both sections are independent, there being no continuity of sections, the angles, however, being greater than in Fig. 1, and 15 acute to the longitudinal axis of the concrete wall. In Fig. 11, the interlocking parts are located upon opposite sides of the longitudinal axis of the wall, when the reinforcement is composite with the wall. In 20 this modification the inward extensions 85 and 86 from two endwise sections each embody along the lines of the longitudinal portions of the sections double U portions 87 and 88, the tie from one side of a section 25 to the other being continuous.

In Fig. 12 a continuous tie 89 is formed by the transverse connection at one end of two sides of a wall section 90 and 91, and the tie bent inwardly, forming two U-shaped 30 bends 93 and 94, transverse to the wall. The interlocking is effected by corresponding 35 bends of a broken tie 92, which interlock, as clearly seen, with the parts 93 and 94, of adjacent sections. Whenever an arch 40 is required to be made, the sections of reinforcement may be similar to that shown in Fig. 1, the sections being obviously short in length, and the portions of the reinforcements for the arch bent to give the gradual inward conformation to the lower portions 45 of the sections, as seen in Fig. 13.

I may, when desired, embody the interlocking of concentric sections 104 and 105, of a column reinforcement, employing the 45 same interlocking tie as seen in Fig. 1, to their segments, and the connecting parts of segments as seen clearly in Fig. 14, the reinforced concentric segments 106 and 107, when thus joined, being a continuation of 50 the curved lines of the wall, as seen in Fig. 1, and obviously the lines of the inner sections will be shorter than the lines of the outer sections.

The completed concrete wall upon the 55 hardening of the concrete is not only fire proof, but resists every penetration of moisture, the portions 31 or 32, of the sections tending to turn the moisture away from the wall, and the advantage consists, in my invention, that when the height of 60 the wall is reached, both inner and outer surfaces are finished surfaces. It being observed, that in finishing the outer surfaces of outer walls the plastic concrete may be 65 given a rough or smooth surface, as the oc-

casion demands. In the construction of concrete structures, the invention reduces the cost to the minimum, dispensing with the costly wooden forms and scaffolding heretofore employed, and the material which is 70 used in plastering the walls by other methods is saved. Furthermore, upon the completion of the height of a building in my invention, the reinforced concrete has hardened so as to sustain any imposed weight 75 that the structure is designed to carry, the walls having been carried up in such stages that the courses have had time to properly harden, and with such advantage that the 80 surfaces are completely finished.

Having fully described my invention, what I now claim as new and desire to secure by Letters Patent is:

1. A reinforcement for concrete structures, consisting of a body plate, bent intermediate its ends to form reversed double U-shaped portions constituting a spacing member between two side members in parallel planes, each side member being integral with and bent from one of the outer edges of the 90 spacing member and having inwardly-extended outwardly-bent U-shaped portions with its parts slightly larger and parallel with the corresponding U-shaped portion of the spacing member contiguous to the respective side member.

2. A reinforcement for concrete structures comprising compartments formed of interlocking sections or plates, a single section being composed of a continuous body plate 100 whose intermediate portion is bent transversely to the body plate from two points distanced from the respective ends of the plate to form a spacing member between two side members in parallel planes, each 105 spacing member being composed of a short intermediate portion extending transversely to the body portion, from which extend in opposite directions short portions or offsets, and from which offsets are extended in opposite directions and transversely to the body section the remaining portions of the spacing member which connect with the outer edges of the side members, the latter 110 portions and offsets forming reversed double U-shaped portions of the spacing member, the ends of the side members being provided with inwardly-extended outwardly-bent portions adapted to inclose telescopically 115 with one of the U-shaped portions of the spacing member of an adjacent section.

3. In concrete walls and similar structures, a reinforcement formed of body sections or plates in parallel planes, transverse spacing members or plates integral with the body sections, and studs integral with the spacing members or plates, bi-secting the longitudinal axis of the structure, each spacing member and said studs being composed of a short intermediate portion extending 120

transversely to the body section, from which extend in opposite directions short portions or offsets, and from which offsets are extended in opposite directions and transversely to 5 the body section the remaining portions of the spacing member which connect with the body section forming with the said offsets reversed double U-shaped portions, and separate external U-shaped grasping portions

of the body sections adapted to grasp the 10 corresponding U-shaped portions of the reversed double U-shaped portions of the spacing member of an adjacent section.
